UNITED STATES PATENT OFFICE.

MARSHALL B. LLOYD, OF MENOMINEE, MICHIGAN, ASSIGNEE, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

REED ARTICLE AND METHOD OF MAKING THE SAME.

Application filed July 13, 1921. Serial No. 484,393.

To all whom it may concern:

Be it known that I, MARSHALL B. LLOYD, a citizen of the United States, and a resident of Menominee, county of Menominee, and 5 State of Michigan, have invented a certain new, useful, and Improved Reed Article and Method of Making the Same, of which the following is a specification.

My invention relates generally to the production of woven reed articles by the general method disclosed in my prior Patents 10 Nos. 1,243,079, 1,243,080, 1,243,081, and 1,243,082, that is to say to a reed article which is composed in part of the frame and in part 15 of a woven reed fabric of the kind defined in my former patents, and which embodies a reed or reed-like fabric formed independently of the frame and thereafter applied thereto. More specifically, my invention relates to the production of woven reed 20 articles from strips of fabric from which it is desired to produce tubular articles.

In making articles embodying therein an independently woven reed fabric, i. e., a 25 stake and strand fabric whether of the natural reed or so-called fibre reed, I find it highly desirable to affix metallic binder strips to the edge portions of the fabric. These metallic binder strips serve a 30 number of very useful and important purposes, such for example as preventing disintegration of the fabric, in facilitating manipulation of the fabric, and in making easy the application of the fabric 35 to the frame. Such metallic edge binders, however, as heretofore used, are objectionable in that their presence is readily detected and serves to mar the beauty of the article. Since reed articles are designed quite 40 as much for beauty as for utility this is a serious objection.

It is an object of my invention to provide a reed article and a method of making the same wherein a metallic edge binder can be 45 successfully used and, at the same time, in the completed article, shall be wholly invisible.

My invention also consists in an article of manufacture, and in the steps, acts and 50 stated sequence thereof whereby the above named objects, together with others that will appear hereinafter are attainable, and my invention will be more readily understood

by reference to the accompanying drawings, which illustrate what I consider at the 55 present time to be the preferred embodiment thereof.

In said drawings:

Fig. 1 is a view of a piece of woven reed or reed-like fabric having metallic edge 60 binders thereon.

Fig. 2 is an enlarged sectional view substantially along the line 2—2 of Fig. 1.

Fig. 3 is a view of the fabric shown in Fig. 2 but indicating the next step in the 65 manufacture.

Fig. 4 is an enlarged sectional view substantially on the line 4—4 of Fig. 3, the central part of the fabric being omitted or broken away for lack of space. 70

Fig. 5 is a perspective view of a reed article embodying my invention; and

Fig. 6 is an enlarged sectional view substantially on the line 6—6 of Fig. 5. 75

The fabric, which may be woven in any desired manner and which may be composed of the natural reed, fibre reed and the like, embodies, therein a plurality of spaced stake members 1 over and under which filler strands 2 are woven. To the ends of the fabric are affixed metallic binder strips 3 and 4. These binder strips, as is well shown in Fig. 2, are U-shaped in cross-section, thus forming a channel for the reception of the ends of the filler strands. These metallic 80 edge binders are firmly pressed upon the filler strands and thus tightly grip them, in such manner, as positively to prevent any loosening of the fabric and any displacement of the stakes. 85

For illustrative purposes I have depicted the manufacture of a chair and particularly of the bottom or skirt portion thereof which is tubular in form, and which is to be made from the flat strip of material 90 already described.

After affixing the metallic edge binders to the fabric I fold them backwardly upon the fabric as is well shown in Fig. 4. I then wrap the fabric of Fig. 4 around the 100 legs 5, 6, 7 and 8 of the chair, preferably so positioning the fabric that the ends thereof shall terminate intermediate the rear legs 7 and 8 of the chair, since this is the most inconspicuous place. Now it will be observed that one edge binder 4 is placed un- 105

der the other edge binder 3, i. e., the edge binder 3 overlaps the portion of the fabric which lies over the metallic binder 4.

To secure the fabric in place the filler strands are separated and one or more brads or other fastening devices 9 are driven through both metallic edge binders 3 and 4. After the fastening devices 9 have been driven into place the filler strands, which have previously been spread apart to permit the driving of the fastening devices, are replaced and thus entirely hide the fastening devices. Following this practice it is apparent that the metallic edge binders are entirely hidden from view and also that by overlapping the ends the stakes are relatively close together. Thus the article looks very much as though it were made of a continuous piece woven tubular in form. Furthermore the article can be made very quickly, at low cost and is well adapted to the purpose intended.

Such modification may be made as is within the scope of the appended claims without departing from the invention.

I claim:—

1. The herein described method of producing woven reed articles of tubular form from non-tubular fabric that consists in providing a non-tubular piece of woven reed fabric, securing metallic binder strips to opposite end portions thereof, forming the fabric into tubular shape, and bringing the metallically bound end portions into proximate relation, meantime folding the metallic binder strips back upon that face of the fabric that forms the inner face in the completed article.

2. The herein described method of producing woven reed articles of tubular form from non-tubular fabric that consists in providing a non-tubular piece of woven reed fabric, securing metallic binder strips to opposite end portions thereof, forming the fabric into tubular shape around a frame, and bringing the metallically bound end portions into proximate relation, meantime folding the metallic binder strips back upon that face of the fabric that forms the inner face in the completed article.

3. The herein described method of producing woven reed articles of tubular form from non-tubular fabric that consists in providing a non-tubular piece of woven reed fabric, securing metallic binder strips to opposite end portions thereof, folding the binder strips back upon that side of the fabric that in the finished article is the inner side, forming the fabric into tubular shape,

meantime bringing the metallically bound end portions into superposed relation and fastening said end portions together.

4. The herein described method of producing woven reed articles of tubular form from non-tubular fabric that consists in providing a non-tubular piece of woven reed fabric, securing metallic binder strips to opposite end portions thereof, folding the binder strips back upon that side of the fabric that in the finished article is the inner side, forming the fabric into tubular shape, meantime bringing the metallically bound end portions into superposed relation and fastening said end portions together by a device which pierces both metallic binder strips.

5. The herein described method of producing woven reed articles of tubular form from non-tubular fabric that consists in providing a non-tubular piece of woven reed fabric, securing metallic binder strips to opposite end portions thereof, folding the binder strips back upon that side of the fabric that in the finished article is the inner side, forming the fabric into tubular shape around a frame, meantime bringing the metallically bound end portions into superposed relation and fastening said end portions together.

6. The herein described method of producing woven reed articles of tubular form from non-tubular fabric that consists in providing a non-tubular piece of woven reed fabric, securing metallic binder strips to opposite end portions thereof, folding the binder strips back upon that side of the fabric that in the finished article is the inner side, forming the fabric into tubular shape around a frame, meantime bringing the metallically bound end portions into superposed relation at the back of the frame, and fastening said end portions together.

7. The herein described method of producing woven reed articles of tubular form from non-tubular fabric that consists in providing a non-tubular piece of woven reed fabric, securing metallic binder strips to opposite end portions thereof, folding the binder strips back upon that side of the fabric that in the finished article is the inner side, forming the fabric into tubular shape around a frame, meantime bringing the metallically bound end portions into superposed relation at the back of the frame, and fastening said end portions together.

In testimony whereof, I have hereunto set my hand, this 22nd day of June, 1921.

MARSHALL B. LLOYD.
